(57) **CLAIM**

The ornamental design for the television set, as shown and described.

DESCRIPTION

FIG. 1 is a perspective view of a television set showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view illustrating an alternate position, placing the television set on a couch; and,

FIG. 9 is a perspective view illustrating an alternate position, folding up the television set.

The broken lines shown in FIG. 8 are for illustrative purposes only and form no part of the claimed design.
